Primary Examiner — Cynthia Underwood(74) *Attorney, Agent, or Firm* — Scheinberg & Associates, P.C.; Michael O. Scheinberg**CLAIM**

I claim the ornamental design for a hose holder, as shown and described.

DESCRIPTION

FIG. 1 is a perspective view of a hose holder showing my new design;

FIG. 2 is a front elevation of the hose holder of FIG. 1; FIG. 3 is a rear elevation of the hose holder of FIG. 1; FIG. 4 is a left side elevation of the hose holder of FIG. 1; FIG. 5 is a right side elevation of the hose holder of FIG. 1; FIG. 6 is top plan view of the hose holder of FIG. 1; and, FIG. 7 is a bottom plan view of the hose holder of FIG. 1. The broken lines represent a hose and the ground and form no part of the claim.

1 Claim, 4 Drawing Sheets(56)
